UNITED STATES PATENT OFFICE.

ALBERT F. BREITENSTEIN, OF NEW HAVEN, CONNECTICUT, ASSIGNOR TO THE GEOMETRIC TOOL CO., OF NEW HAVEN, CONNECTICUT, A CORPORATION.

SELF-OPENING DIE HEAD.

Application filed June 25, 1924. Serial No. 722,278.

I do hereby declare the following, when taken in connection with the accompanying drawings and the characters of reference marked thereon, to be a full, clear and exact 5 description of the invention, and which said drawings constitute part of this application, and represent, in—

Fig. 1 a view in front elevation of a self-opening die-head constructed in accordance 10 with my invention.

Fig. 2 a view thereof in side elevation.

Fig. 3 a view thereof in central, longitudinal section.

Fig. 4 a broken, sectional view on the line 15 4—4 of Fig. 1.

Fig. 5 a corresponding view on the line 5—5 of Fig. 1.

Fig. 6 a broken view in front elevation of the die-head body, stripped.

Fig. 7 a detail, perspective view showing 20 the four, segmental, chaser-retaining plates.

My invention relates to an improved self-opening die-head, whether stationary or rotary, the object being to produce a simple, 25 compact, convenient and durable die-head constructed with particular reference to its adaptability to be used in threading close to a shoulder, and to giving the chasers the maximum amount of support, and hence securing for them stability of position and 30 precision of performance.

With these ends in view, my invention consists in a self-opening die-head having certain details of construction and combination 35 of parts as will be hereinafter described and particularly recited in the claim.

In carrying out my invention, as herein shown, I employ four equidistant chasers 10 respectively located in as many radial 40 grooves 11 in the face of a skeleton die-body 12 having a hollow shank 13. The said chasers project between and are held in place by four corresponding segmental chaser-retaining plates 14 secured to the forward face 45 of the body 12 by rivets 15, as clearly shown in Fig. 1, these four segmental plates taking the place of the ordinary annular retaining ring commonly employed for holding the chasers of self-opening die-heads in place.

50 As herein shown, the corresponding forward corners of the chasers are cut back to form shoulders 16, over which the edges of the said plates 14 rest, so as to retain the chasers in place without interfering with 55 their free radial movement. Under this con-

struction, the forward faces of the chasers may be projected to any desired extent beyond the plane of the chaser-retaining plates 14 without weakening the support which the chasers receive from the die-body and plates. 60

The extension of the chasers forward between the means employed to retain them in place permits them to be used for threading a shouldered object close to its shoulder, which cannot be done with the self-opening 65 die-heads of the prior art without weakening the die-head structure and endangering the precision of its operation, notably in resorting to chasers of too delicate shape to withstand the work demanded of them. 70

As shown, the opening movement of the chasers is effected by their provision upon their inner edges with pins 17 engaged by spring-actuated plungers 18 located in radial bores 19 in the die-head body 12, as shown 75 in Fig. 3.

For moving the chasers inward into their cutting positions, their beveled outer edges 20 are engaged by the beveled forward end of an operating-sleeve 21, which rides back 80 and forth upon an adjusting-ring 22 internally-threaded for being screwed upon the threaded portion of the shank 13 of the body 12. The sleeve 21 is guided in being so moved back and forth by two guide-pins 23 85 carried by it and extending forward into bores 24 in the body 12, as shown in Fig. 5. For moving the sleeve rearward to permit the self-opening of the chasers, I employ two springs 26, the respective ends of which are inserted into bores 27 in the sleeve 21 and 90 bores 28 in the body 12, as shown in Fig. 4.

For locking the sleeve in its closed position, in which the chasers are held in their advanced or cutting positions, I may employ 95 any approved form of locking device. As herein shown, I employ for the purpose, a locking device of my invention forming the subject-matter of an application filed of even date herewith, the said device consisting of a tripping-member 29, a locking-member 30, a filler-member 31, and springs 32 (only one of which is shown herein) exerting a constant effort to force the locking-member outward for its engagement 100 with an abutment-shoulder 33 upon the interior of the sleeve 21.

I would, therefore, have it understood that I do not limit myself to the use of my improved chasers and means for mounting the 110

same with such a tripping device as herein shown and described, nor with any particular tripping device.

I am aware that a self-opening die-head having segmental chaser-retaining plates is old, and do not claim the same broadly.

I claim:—

In a self-opening rotary die-head, the combination with a one-piece body provided 10 with an integral tubular shank and having its front face formed with radial chaser-receiving slots, of radially-movable chasers having sliding bearing directly in the said slots and each having one flat side and one 15 shouldered side and each having its outer end beveled and formed at its inner end with cutting-teeth; springs for moving the said chasers radially outward, an operating-sleeve axially movable with respect to the 20 said body and engaging, at its forward end,

with the beveled outer ends of the said chasers for forcing the same inwardly when the sleeve is moved forward; and segmental chaser-retaining plates permanently fastened to the front face of the said body and 25 positioned thereupon, so that one end of each plate is flush with one wall of one of the said radial slots therein and so that its opposite end overhangs the wall of an adjacent slot for engagement with the single shoulder 30 of the chaser therein, whereby the said chasers may be inserted into and removed from the said chaser-receiving slots by retiring the sleeve from front to rear and without necessitating the removal of any of the said 35 chaser-retaining plates or the removal from the tool of the said sleeve.

In testimony whereof, I have signed this specification.

ALBERT F. BREITENSTEIN.
